UNITED STATES PATENT OFFICE.

GUSTAF A. STARK, OF ATWATER, MINNESOTA.

GRAVE COVERING AND LINING DEVICE.

Application filed November 15, 1926. Serial No. 148,348.

This invention relates to grave covering and lining devices.

It is the object of this invention to provide in connection with a casket lowering device, means for concealing the lowering device and for lining a grave as a casket is lowered therein by the lowering device.

It is a further object to operate said means by the rotatable side members of a lowering device.

These and other objects and advantages of the present invention will more fully appear from the following description made in connection with the accompanying drawings wherein like reference characters refer to the same or similar parts throughout the various views and in which,

Fig. 1, is a perspective view showing the use of one embodiment of the present invention in connection with a casket lowering device, having a casket placed thereon in position for lowering into a grave,

Fig. 2, is a plan view of one embodiment of the invention, as applied on a standard casket lowering device, certain of the parts being broken away,

Fig. 3, is a vertical section taken on the line 3—3 of Fig. 2, as indicated by the arrows, certain of the movable parts being shown in full lines in one position and in dotted lines in another position,

Fig. 4, is a vertical section taken on the lines 4—4 of Fig. 2, as indicated by the arrows;

Fig. 5, is a vertical section taken on the line 5—5 of Fig. 2, as indicated by the arrows and;

Fig. 6, is an enlarged view showing one portion of the lowering device, certain of the parts being broken away.

Referring to the drawings, a casket lowering device of standard construction is illustrated including corner posts 7, side shafts 8, end shafts 9, and webbing straps 10 extending between the two side shafts 8, the ends of the webbing straps being releasably secured to the shafts 8 by staples 11 and wound upon the shafts. A foot control pedal 12 is used for controlling the lowering of the device and a crank 13 for winding up the webbing straps 10 on shafts 8 before or after using the device. Shafts 8 are preferably composed from tubing and have removable central sections 14 slidably securable in the main sections by pin and socket joints, small keys being formed at each joint

to permit sections 14 and the main sections of the shafts 8 to rotate as a whole. The lowering device is of substantially rectangular shape and is adapted to be set up and situated over an open grave, whereupon a casket, such as the casket 15, may be placed on the webbing straps 10 and the foot control pedal 12 pressed downwardly to permit the weight of the casket to carry the same downwardly into the grave, the shafts 8 rotating towards each other as the casket sinks into the grave.

In accordance with the present invention, a rectangular frame is provided which is adapted to be placed to rest on the ground to surround the lowering device. The frame is of pipe joint construction and includes the elbows 16, side sections 17, central side sections 18, end sections 19 and end sections

20. Unions 21 secure the side sections 17 to the central side sections 18, the remaining sections being screwed into the elbows 16, the sections 19 and 20 being slidably joined together as at 22 by pin and socket joints.

Hooks 23 having riveted, or otherwise secured thereto at their inner side portions, friction strips 24, composed preferably from some rather hard type of gripping material such as hard rubber, are placed over the shafts 8 adjacent the ends thereof, hooks 23 being bifurcated at their inner ends and turned inwardly to form half hinge portions.

Rods 25 forming portions of wings to be hereinafter described, are extended through the half hinge portions of hooks 23, forming pivots about which the hooks may be swung, plates 26 being secured to rods 25 between the bifurcated portions of hooks 23. Blocks 27, having concavely curved outer surfaces conforming preferably to the curvature of shafts 8, are secured to plates 26 preferably by means of bolts 28, spacing plates 29 being preferably interposed between the plates 26 and blocks

27 and strips 30, of some soft friction gripping material such as soft rubber, surrounding the blocks 27 and being secured thereto by the bolts 28. The wings above referred to are of substantially C-shape and are preferably of pipe joint construction comprising elbows 31, ends 32, rods 25, short rods 33, inner side portions 34 slidably by pin and socket joints upon portions 33, and intermediate side portions 35 connected by unions

36 to side portions 34. The wings are extended inwardly from hooks 23 when in

75

80

idle position, as illustrated in Fig. 2, and are preferably of such length that their ends will be spaced but a short distance from the end shafts 9 of the lowering device, while the wings are of such width that when horizontally extended there will be but slight space between respective portions 34 and 35 of the respective wings. End shrouds 37 formed from sheets of flexible material are connected at their outer sides to the end sections 19 of the frame by hooks 38 secured in rings in the shrouds, the shrouds 37 then being extended over the corner posts 7 and shafts 9 of the lowering device to depend downwardly into the open grave. Additional hooks 38, similarly secured to rings in the edges of shrouds 37, may be used for connecting the edges of shrouds 37 to the side sections 17 of the frame. Shrouds 39 are secured at their outer ends by hooks 38 to the side sections 17 and 18 of the frame, the hooks being secured in rings in the shrouds. Shrouds 39 have slits 40 cut therein through which the webbing straps 10 are extended, the shrouds extending over the side shafts 14 of the lowering device, over the wings and depending downwardly between the inner sides of the respective wings into the grave. Shrouds 39 are also preferably composed from sheets of flexible material similar to the material composing the shrouds 37.

Preferably the various parts of the device will be taken all apart for transportation or storage when not in use. To assemble the device, elbows 16 and sections 17, 18, 19 and 20 are screwed together whereupon sections 20 and 22 may be fitted together to form the rectangular frame. The frame is then placed on the ground immediately surrounding an open grave, having a casket lowering device placed thereover. Members 25 having hooks 23 secured thereto, and members 31, 32, 33, 34, 35 and 36 are then assembled together to form the wings of the device. Hooks 23 are then placed over the shafts 8, the outer portions of the wings being placed beneath the webbing straps 10, whereupon the outer portions of the wings are raised upwardly and the strips 30 of friction material secured to clamping blocks 27, are engaged with the shafts 8 to rigidly secure the wings on the shafts with the wings extending inwardly from the shafts 8 in substantially a horizontal plane. The weight of the wings when horizontally extended will cause hooks 23 and blocks 27 to clamp tightly against the shafts 9 to prevent rotation of the wings in respect to the shafts. Webbing straps 10 of the lowering device are now disconnected at their ends and slipped through slits 40 in shrouds 39, whereupon the ends of the webbing straps are again secured to shafts 8 by clips 11 and wound thereupon. Shrouds 37 are then

hooked on the end members 19 and side members 17 of the frame shafts and are run over the end shafts 9 and corner posts 7 to extend downwardly into the open grave. Shrouds 39 are also hooked to the members 17 and 18 of the frame whereupon they are extended over shafts 8 and the wings, to rest upon the wings and depend downwardly between the inner sides of the respective wings into the open grave. The device is now ready for use at a burial ceremony. When the parts are in such position the entire lowering device will be concealed with the exception of the webbing straps 10.

A casket 15 may now be placed upon the webbing straps 10 whereupon the casket may be lowered into the grave. As the foot control pedal 12 of the lowering device is pressed, the weight of the casket 15 will carry the same downwardly into the grave thereby rotating the shafts 8. As the shafts 8 are rotated, the wings will be swung therewith downwardly into the grave until the inner sides of the wings will strike the sides of the grave as illustrated in dotted lines Fig. 3, whereupon as downward movement of the casket continues, hooks 23 will pivot about rods 25 thereby permitting friction strips 30 and blocks 27 to move away from the shafts 8 and permitting shafts 8 to rotate in respect to hooks 23 and the wings. Shrouds 39 will have followed the wings downwardly into the grave and accordingly will hang adjacent the sides of the grave to line the sides thereof. Shrouds 37 will have already been extended into the grave to line the ends thereof. Accordingly the grave will be completely lined and will present an attractive appearance covering up all sight of the offensive bare earth forming the grave wall. The shrouds 37 and 39 may be formed from some attractive material, such as flexible sheeting representing natural grass, or the like, thereby giving a pleasing effect.

If it is desired to use the device of the invention in connection with caskets of smaller sizes, sections 18 may be removed from the frame and members 35 from the wings together with section 14 of the casket lowering device, whereupon the shafts of the lowering device and of the frame and of the wings may be shortened to be of proper length for use with smaller caskets. Similarly additional sections may be added to the frame and wings for use with longer caskets. Also if the invention is used in connection with a casket lowering device having shafts 8 of various diameters, strips 29 of various sizes may be used to space blocks 30 closer or farther away from hooks 23 as desired. The construction of the wings and frame may be varied considerably if desired, various types of connections being capable of being used.

Friction strips 24 secured to hooks 23 are

preferably made from some rather hard material, such as hard rubber, so that the shafts 8 may readily rotate after the wings have been lowered without binding on the strips.

5 As strips 30 bear the brunt of the clamping action, they are made of soft material so that there will be no danger of the blocks 27 slipping away from the shafts 8 until the wings are lowered. Straps 30 as they become worn out may be easily replaced by merely removing bolts 28 and replacing the old straps by new.

10 The device has been extensively used in actual practice and has been found to be very efficient and attractive. The parts of the device are few and of simple construction. The device can be readily disassembled and packed in small compass for removal or storage. The device of the invention may be 15 used with any type of casket lowering device.

15 It will of course be understood that various changes may be made in the form, details, arrangement and proportions of the 20 various parts without departing from the scope of the present invention, which generally stated consists in the matter shown and described and set forth in the appended claims.

25 30 What I claim is:

1. In combination, a casket lowering device and flexible means for lining a grave as a casket is lowered therein by said device.

2. In combination, a casket lowering device and flexible means for concealing said lowering device and for lining a grave as a casket is lowered therein by said device.

3. In combination, a casket lowering device and flexible shrouds concealing said device and operated thereby to line a grave as a casket is lowered therein by said device.

4. In combination, a casket lowering device, a continuous flexible casket lowering device cover and grave liner and means for 45 operating said cover and liner by said lowering device to move the same downwardly into a grave to line the same, as a casket is deposited in the grave by said lowering device.

5. In combination, a casket lowering device adapted to extend over an open grave, flexible means covering said device and adapted to extend into a grave and means adapted to be operated by said device for 55 causing said first mentioned means to line the sides of the grave as a casket is lowered therein by said device.

6. In combination, a casket lowering device, a pair of wings extending inwardly 60 from the sides of said device, shrouds fitting over said lowering device and over said wings and adapted to extend into a grave, and means for securing said wings to said lowering device in such manner as to allow 65 said wings to swing downwardly into a

grave as a casket is deposited therein by said lowering device thereby causing said shrouds to line the sides of the grave.

7. The combination with a casket lowering device having side members adapted to be rotated towards each other, of wings adapted to be releasably secured one to each of said side members, friction lock and release hinges adapted to secure said wings to said side members and shrouds extending over said side members and extending over and supported by said wings, said locks being adapted to hold said wings in rigid connection with said side members as a casket is lowered by said device until said side members have been rotated to permit said wings to strike the sides of a grave, whereupon said locks will be released from rigid engagement with said side members to permit the same to rotate in respect to said wings.

8. In combination a casket lowering device, having side members thereon rotatable towards each other, said casket lowering device being adapted to be placed over an open grave, wings adapted to be respectively secured to each of said side members, shrouds supported on each wing, each shroud extending over one of said side members, and clamping locks secured to each of said wings and adapted to engage with said respective side members to permit said wings to be swung downwardly into a grave by said side members as the same are rotated until said wings strike the sides of the grave, whereupon said clamping locks will be released from said side members to permit said wings to discontinue rotation as said side members are further rotated.

9. The combination with a casket lowering device adapted to be placed over an open grave, and including a substantially rectangular frame with side shafts rotatable towards each other, of flexible sheets adapted to extend over the ends of said frame and into the grave to line the ends of the grave, flexible sheets adapted to extend over the sides of said frame and into the grave and means adapted to be releasably carried by said rotatable shafts for supporting said second mentioned sheets to carry the same downwardly into the grave to line the sides thereof as a casket is lowered therein by said device, said means being releasable from said side shafts after the sides of the grave have been lined, to permit rotation of said shafts in respect to said means.

10. The combination with a casket lowering device, adapted to be placed over an open grave and including a pair of side shafts 125 rotatable towards each other, of wings adapted to be releasably secured to each of said shafts, shrouds fitting over said shafts, resting upon said wings and adapted to extend into the grave, and means for releas-

- ably securing said respective wings to said shafts, whereby as a casket is lowered into the grave by said device, said wings will be swung downwardly into the grave until the 5 wings strike the sides of the grave whereupon said means will automatically release from said shafts to permit said shrouds to line the sides of the grave, and to permit said shafts to rotate in respect to said wings.
- 10 11. The combination with a casket lowering device, adapted to rest over an open grave, and having side shafts rotatable towards each other, of a frame surrounding said lowering device, wings securable to said 15 shafts to extend inwardly therefrom and adapted to be swung downwardly into a grave by said shafts as a casket is lowered by said device into the grave, shrouds secured at their outer sides to the sides of said frame, 20 supported by said wings and extensible into a grave, and shrouds secured at their outer sides to the ends of said frame and extensible into the grave.
12. The combination with a casket lowering device, including a substantially rectangular frame having shafts on the sides thereof rotatable towards each other, of a pair of wings extending when idle inwardly from said shafts, the ends of said wings being 25 spaced a short distance from the ends of said frame and means for releasably clamping said wings on said shafts to cause said wings to swing therewith downwardly into the grave, as a casket is lowered by said device, 30 until the wings strike the sides of the grave whereupon said wings will automatically un-clamp from said shafts, and flexible members resting on said wings and extending downwardly into the grave between the respective 35 wings, said flexible members being adapted to line the sides of the grave as said wings are lowered and flexible members extending over the ends of said frame and downwardly between the ends of said frame and the ends 40 of said wings into the grave, to line the end walls of the grave.
13. The combination with a casket lowering device of general rectangular shape, adapted to rest on the ground over an open 45 grave, and including a pair of rotatable side members, of a frame adapted to rest on the ground around said device, a pair of wings adapted to be respectively secured to the respective rotatable side members of said device, friction clamping locks adapted to secure said wings to said rotatable side members to permit said wings to be swung thereby from an upper position to a straight downward position, whereupon said clamping locks will be released from said side members to permit rotation of said side members in respect to said wings, and flexible sheets secured to said frame and extending inwardly therefrom over said device and wings, said sheets being adapted to extend within the 50 grave to line the sides of the same when said wings are carried to downward position.
14. The combination with a casket lowering device, adapted to be placed over an open grave and having side shafts rotatable towards each other, of hooks fitting over said shafts and extending inwardly therefrom, wings pivoted to said hooks and having clamping jaws rigid therewith adapted to co-operate with said hooks to frictionally hold said wings engaged with said shafts when said wings are in upward position, and sheets of flexible material extending from over said side members and said wings 55 into the grave, whereupon as a casket is lowered by said device into a grave and said shafts are rotated said wings will be frictionally held by said shafts to be swung downwardly into the grave, thereby causing said sheets to line the sides of the grave and permitting said clamping jaws to be released from said side members as said wings strike the sides of the grave to allow rotation of said side members in respect to said 60 wings.
15. The combination with a casket lowering device having side shafts rotatable towards each other, said device being adapted to rest over an open grave, of a frame surrounding said device, hooks resting over said 65 rotatable side members, wings pivoted to said hooks, and extending inwardly from said side members, said wings having friction engaging surfaces at their outer ends adapted to cooperate with said hooks to clamp against said rotatable side members, and flexible sheets secured to said frame resting over said device and said wings and extending into the grave, said wings being adapted 70 to be carried by said rotatable members and to be swung downwardly into the grave as a casket is lowered therein by said device until said wings strike the sides of the grave, whereupon said sheets will line the sides 75 of the grave, and said friction engaging surfaces of said wings will be disengaged from said rotatable members to permit free rotation of said members in respect to said wings.
16. The combination with a casket lowering device adapted to be placed over an open grave, said device having side shafts rotatable towards each other, of hooks adapted to be placed over said shafts, friction blocks pivoted to said hooks and adapted to co-operate with said hooks to clamp about said shafts, wings secured to said blocks and normally extending inwardly from said shafts, the weight of said wings being adapted to tightly clamp said hooks and blocks against said shafts and flexible sheets extending inwardly over said shafts and supported by said wings, the inner ends of said sheets being extensible into a grave, 80 whereby as a casket is lowered into a grave 85

by said device, said wings will be swingable into the grave as said shafts are rotated until the wings strike the sides of the grave, whereupon said blocks will be swung away 5 from said shafts to permit rotation thereof in respect to said wings.

17. The structure defined in claim 16, and means for spacing said respective hooks and blocks varying distances apart to clamp 10 against shafts of various diameters.

18. The combination with a casket lowering device having opposite rollers adapted to be rotated towards each other, of means adapted to be operated by said rollers to 15 line the walls of a grave as a casket is lowered therein by said device.

19. The combination with a casket lowering device, of continuous flexible shrouds adapted to conceal the lowering device and 20 to extend into a grave, and means for op-

erating said shrouds from said lowering device to line the walls of the grave as a casket is lowered therein by said device.

20. The combination with a casket lowering device having side rollers adapted to 25 be rotated towards each other, of wings mounted on said rollers adapted to extend over a grave when said device is in idle position and to be swung downwardly into a grave as a casket is lowered into the grave 30 by said device and shrouds extending over said wings and downwardly into the grave, whereby said shrouds will normally conceal said grave, lowering device and wings when said lowering device is in raised position 35 and will line the walls of said grave when said lowering device is in lowered position.

In testimony whereof I affix my signature.

GUSTAF A. STARK.
